UNITED STATES PATENT OFFICE.

WILLIAM L. BARRON, OF NEWARK, NEW JERSEY, ASSIGNOR TO THE SINGER MANUFACTURING COMPANY, A CORPORATION OF NEW JERSEY.

METHOD OF AND MACHINE FOR ORNAMENTING HOSIERY.

1,361,218.

Specification of Letters Patent.

Patented Dec. 7, 1920.

Application filed October 16, 1919. Serial No. 331,040.

To all whom it may concern:

Be it known that I, WILLIAM L. BARRON, a citizen of the United States, residing at Newark, in the county of Essex and State 5 of New Jersey, have invented certain new and useful Improvements in Methods of and Machines for Ornamenting Hosiery, of which the following is a specification, reference being had therein to the accompanying drawings.

This invention relates to ornamental stitch sewing machines and has for an object to provide a machine of this type which is particularly adapted for sewing arrow-head figures on hosiery to complete the usual ornamentation known as clocking.

Heretofore, arrow-head clocking on hosiery has been formed either by knitting in the ornamental thread or threads or by 20 sewing in the stem of the clocking on an overedge or other straightaway stitching machine after which the arrow-head has been embroidered by hand in position at the upper end of the stem. Also, the entire ornamentation has been produced by hand 25 embroidering.

Methods of clocking involving hand sewing operations are costly to carry into effect and it is also difficult and costly to properly 30 knit in the ornamental threads.

The present invention therefore has for a further object to provide a method of clocking hosiery which may be rapidly carried into effect by machine operations, thereby 35 eliminating the tedious hand work previously found to be necessary.

Further objects of the invention will appear as the description proceeds.

According to the present invention the 40 stem of the ornamentation is sewn as usual by folding the ankle or leg portion of the hose longitudinally and presenting the folded edge to an overcasting or overedge stitching machine, after which the hose is 45 opened out and placed upon the work-supporting horn or cylinder-bed of a second machine adapted to stitch the arrow-head ornamentation in a position with its base substantially at right angles to the axis of 50 the work-supporting horn. The work-support includes opposed guides for laterally locating a filler piece of blotting paper or

the like in position at the under side of the work to form a backing serving to prevent the stitches from puckering the light and 55 elastic work as they are being drawn up. The filler-piece is preferably somewhat larger than the stitched figure and the portions not inclosed by the stitching may be torn away or otherwise removed. The 60 presser-foot of the machine preferably comprises a solid foot-plate formed with a triangular aperture within which the ornamental figure or arrow-head is stitched.

In the accompanying drawings, Figure 1 65 is a side elevation of a machine embodying the invention. Fig. 2 is a perspective view of the free end portion of the work-supporting arm or horn showing the needle and work-holder. Fig. 3 is a top plan view of 70 the upper and lower work-holding elements. Fig. 4 is a side elevation of the same. Figs. 5 and 6 are, respectively, transverse and longitudinal sections through the work-holding elements with the work in position 75 therebetween. Fig. 7 is a section on the line 7—7, Fig. 4. Fig. 8 is a diagrammatic view showing the arrangement of the needle-punctures produced by the present machine in sewing the arrow-head ornamentation. 80 Fig. 9 is a plan view of the completed work and Fig. 10 is a transverse section on the line 10—10, Fig. 9.

In the preferred embodiment of the invention, as illustrated, the machine frame 85 comprises a base 1 from which rises the standard 2 carrying the bracket-arm 3 terminating in the hollow head 4 in which is journaled the needle-bar 5 carrying the eye-pointed needle 6. In practice, the needle 6 90 co-operates with a suitable loop-taker, not shown, within the free end of the hollow work-supporting horn or cylinder-bed 7 which projects forwardly from the base 1 at an elevation above the table-top *a* upon 95 which such machines are customarily stationed. The work-supporting arm or horn 7 carries the usual apertured throat-plate 8 at its forward or free end.

The work is adapted to be clamped between the upper and lower members of a work-holder which, in the particular embodiment illustrated, is moved to and fro over the throat-plate 8 to position the

stitches in accordance with the desired pattern. The present work holder is of the general type disclosed, for example, in my Patent No. 1,205,317, of November 21, 1916, 5 and comprises the supporting bar 9 on which is mounted the bracket 10 having at its free end a head 11 in which is slidably mounted the presser-box 12. Projecting forwardly from the presser-bar 12 through the slot 12^a 10 in the face of the head 11 is the rod 12^b the extremity of which lies above and in the path of vertical movement of the arm 12^c of a bracket-piece fixed to the lower end of the usual manually operated presser-foot lifting bar 12^d journaled in the head 4.

The work-holder is moved longitudinally of the bed 7 by means of the usual cam-slot 13 in the inner face of the cam-wheel 14. This cam-slot imparts rocking motion to the 20 lever 15 which communicates its motion in a manner well known to the vertical post 16 rising from the rearward end of the bar 9. The work-holder is vibrated laterally of the bed 1 about the post 16 as a pivot by means 25 of the usual connections with the cam-slot 17 in the outer face of the cam-disk 14. These connections include the bellcrank-lever 18, pitman 19 and rock-shaft 20, all as more fully described in the patent to Horton No. 30 1,051,998 of February 4, 1913. It is understood that a machine of the present type operates automatically, when tripped into action, to stitch the desired pattern in the work and then come to rest; the usual stop-motion 35 being provided to control the period of action of the machine.

Secured to the front end of the bar 9 is the lower or work-supporting plate 21. This plate is provided with a stitching aperture 40 22 having the form of an isosceles triangle arranged with its base 23 substantially at right angles to the longitudinal axes of the bar 9 and work-supporting arm 7. Stated in another way, the stitching aperture 22 is 45 so disposed that its axis of symmetry represented by the dotted line extending from the point 35 to the point 36 in Fig. 8 extends lengthwise of the work-supporting arm 7. The plate 21 carries the upstanding guide-walls 24 at the opposite sides of the aperture 22 and the guide-wall or stop 24' at the rear of said aperture. These guide-walls, 24, 24', together with the plate 21 50 form a holder for a suitable filler-piece to be stitched to the under side of the work. It will be noted that this holder is open at its front end to permit the insertion of the filler-piece between the guide-walls 24 and into engagement with the stop-wall 24' by a 55 longitudinal sliding movement and without the necessity of carefully locating and pressing the filler-piece vertically into sewing position. The guide-walls 24 diminish in height toward their forward ends and the 60 rearward wall 24' is cut away, as at 25, to 65

avoid undue puckering of the goods as it is pressed into position between the walls 24 by the presser to be described.

The presser-bar is provided at its forward end with a forward extension 26 which, at 70 its free end is formed into a flat foot-plate or presser 27 having a triangular aperture 28 similar to and substantially in register with the aperture 22 in the work-supporting plate 21. The width of the presser-foot 27 75 is somewhat less than the distance between the side guide-walls 24 so that said foot may enter the space between said walls and clamp the work firmly against the work-supporting plate 21.

Prior to the operation of the machine, it is understood that the hose 29 has first received the stem ornamentation as, for example, by being folded longitudinally and presented to an overedge machine to form the line of 80 ornamental stitches 30 lengthwise of the wales 31. As overedge machines usually produce a readily raveling stitch, the stitching 30 is started at a point near the ankle of the hose and extends upwardly toward 90 the point 32 where the arrow-head ornamentation 33 is to be placed; the arrow-head being depended upon to anchor the finishing end of the seam 30 and prevent raveling of the latter.

With the presser-foot 27 elevated, the operator then slides the filler-piece 34 horizontally between the guide-walls 24 and into engagement with the stop 24' without vertical movement, there being no obstruction at 100 the front of the space between said walls 24, and places the open end of the hose over the horn 7 with the end 32 of the seam 30 directly beneath the aperture 28 in the presser-foot 27 so that when the presser-foot is 105 lowered the triangular aperture 28 will expose the upper end of the initially stitched seam at substantially the center of the base of said aperture.

When the machine is started, the needle 110 makes the first stitch at the point 35, Fig. 8, within the overseam 30 and, as the work-holder is shifted forwardly, the stitching proceeds toward the apex 36 of the triangle, whereupon to-and-fro lateral vibratory 115 movements are imparted to the work-holder as the latter is slowly retracted, thereby placing the needle-punctures alternately at opposite sides of the triangle. When the bottom of the triangle is reached, a few 120 appropriate finishing stitches are placed along the base and the final tying stitches are placed at the point 35 after which the machine comes to rest. After the work is removed from the machine, the operator 125 tears away or otherwise removes the uncovered portion of the filler-piece leaving the finished work as shown in Figs. 9 and 10. Although it is possible to do the above described work on a flat bed machine 130

it will be readily understood from the foregoing disclosure that the combination afforded by the use of the tubular work-supporting arm over which the hose may be readily placed without distortion, together with stitch-forming mechanism and a work-holder adapted to produce a stitched figure having its axis of symmetry disposed lengthwise of the work-supporting arm, is particularly desirable for sewing clocking on hosiery.

Having thus set forth the nature of the invention, what I claim herein is—

1. A sewing machine for clocking hosiery having, in combination, stitch-forming mechanism, a work-support, means on the work-support for positioning a filler-piece in sewing position at the underside of the work, a presser-foot having a foot-plate formed with a sewing aperture, and means for relatively moving the stitch-forming mechanism and presser-foot to lay the sewing threads across from one to the other side of said aperture and progressively along the length of said aperture, thereby substantially covering with stitches the area of material exposed within said aperture.

2. In a sewing machine, in combination, stitch-forming mechanism, a work-support, means on the work-support having side and bottom walls for positioning and supporting a filler-piece in sewing position at the under side of the work, a presser-foot having a foot-plate formed with a sewing aperture, and means for relatively moving the stitch-forming mechanism and presser-foot to substantially cover with stitches the area of material exposed within the aperture of the presser-foot.

3. An ornamental stitch sewing machine having, in combination, stitch-forming mechanism, a work-holder including a work-supporting plate formed with an apertured bottom wall for supporting a filler-piece and having spaced guiding means rigid with said bottom wall for laterally positioning the filler-piece over the aperture therein, a presser-foot having an aperture registering with the aperture in said bottom wall, and means for relatively moving the stitch-forming mechanism and work-holder to substantially cover with stitches the area of material exposed within the aperture of the presser-foot.

4. An ornamental stitch sewing machine having, in combination, stitch-forming mechanism, a work-holder comprising a work-supporting plate formed with an apertured bottom wall for supporting a filler-piece and having spaced guiding means rigid with said bottom wall for laterally positioning the filler-piece over the aperture therein, an apertured presser-foot adapted to be received between said spaced guiding means, and means for relatively moving the stitch-

forming mechanism and work-holder to substantially cover with stitches the area of material exposed within the aperture of the presser-foot.

5. A sewing machine for clocking hosiery having, in combination, a frame including a tubular work-supporting arm, stitch-forming mechanism incorporated in said frame, a work-holder including means on the work-supporting arm for laterally positioning a filler-piece at the under side of the work, a vertically movable presser-foot having an aperture so disposed that an axis of symmetry of said aperture extends lengthwise of said arm, and means for relatively moving the stitch-forming mechanism and work-holder to substantially cover with stitches the area of material exposed within the aperture of the presser-foot.

6. A sewing machine for clocking hosiery having, in combination, a frame including a tubular work-supporting arm, stitch-forming mechanism incorporated in said frame, a work holder including spaced guiding means for laterally positioning a filler-piece at the under side of the work, a vertically movable presser-foot having a triangular aperture disposed with its base substantially at right angles to the longitudinal axis of said arm, and means for relatively moving the stitch-forming mechanism and work-holder to substantially cover with stitches the area of material exposed within the aperture of the presser-foot.

7. A sewing machine for clocking hosiery having, in combination, a frame including a standard and a work-supporting horn free at one end and at its opposite end joined to the standard above the base of the latter, a work-holder mounted on said horn and including work-support and presser members formed with registering triangular apertures with the bases of said apertures extending substantially at right angles to the longitudinal axis of said horn, stitch-forming mechanism incorporated in said frame, and means for producing relative stitch-positioning movements between said stitch-forming mechanism and work-holder to substantially cover with stitches the area of material exposed within the aperture of the presser-foot.

8. A work-holder for ornamental stitch sewing machines having, in combination, an apertured work-supporting plate including a substantially flat bottom wall for supporting a flat filler-piece, upstanding guiding means at opposite sides of the aperture of said plate to laterally position the filler-piece over said aperture at the under side of the work, and a correspondingly apertured vertically movable presser-foot adapted to be received within the space defined by said guides.

9. The method of clocking knitted hosiery which comprises, sewing a straightaway line of ornamental stitches longitudinally of the

- wales of the hose, assembling the hose thus prepared over the arm of a cylinder-bed machine with a filler-piece against the inner surface of the hose at the upper extremity of
5 the first-made line of stitches, operating the machine to sew through the hose and filler to form an ornamental group of stitches cov-

ering and anchoring the upper end of the first line of stitches and, lastly, removing the portions of the filler-piece which are not included in the stitched figure. 10

In testimony whereof I have signed my name to this specification.

WILLIAM L. BARRON.
